UNITED STATES PATENT OFFICE.

BENJAMIN F. DAVIS, OF CORSICANA, TEXAS.

CANTALEVER.

SPECIFICATION forming part of Letters Patent No. 311,064, dated January 20, 1885.

Application filed August 6, 1884. (No model.)

To all whom it may concern:

Be it known that I, BENJAMIN F. DAVIS, a citizen of the United States, and a resident of Corsicana, in the county of Navarro and State 5 of Texas, have invented certain new and useful Improvements in Cantalevers; and I do hereby declare that the following is a full, clear, and exact description of the invention, which will enable others skilled in the art to 10 which it appertains to make and use the same, reference being had to the accompanying drawing, which forms a part of this specification, and which represents a side view of my invention.

15 My invention has relation to trusses for bridges or similar structures constructed on the principle of a so-called cantalever; and it consists in the improved construction and combination of parts of the same, as hereinafter 20 more fully described and claimed.

In the accompanying drawing, the letter A indicates an upright post or column supported upon a suitable pier or tower, and two beams or struts, B B, project in opposite 25 directions from the base of the post, preferably as shown in the drawing, slightly inclined in an upward direction, although the beams may project horizontally from the base of the post. Rods, bars, or cables C extend from 30 the top of the post to the ends of the beams supporting the outer ends of the same, and a number of rods, bars, or cables, e, project from the top of the post to different points along the beam, preventing any sagging of 35 the same. The outermost of these latter rods, bars, or cables, E, passes through the beam and is secured to the end of the same, and a brace, n, extending from the strut nearest to the shore end of the same, serves to take up the 40 slack in the said extended end of the rod, bar, or cable, and to cause the weight upon that beam or strut to exert an upward pressure upon the outer end of the beam or strut. Supplemental braces e' extend from near the 45 inner ends of the beams to the central post, being secured to the same below its end, and preferably near or at its middle. Rods, bars, or cables f extend from near or at the middle of the post to the ends of the beams, when the 50 latter are inclined, and an oblique brace, g, extends from the outer rod, bar, or cable at the long or shore end of the structure to the beam or strut, serving to furthermore divide

the strain upon the beam or strut, the shore or longer arm of the structure serving as a 55 counterpoise for the weight falling upon the outer end of the structure, and when the struts or beams are in their inclined position, which position is shown in the drawing, and which position is the most preferable, the stringers 60 j of the bridge, upon which the cross-pieces or sleepers of the bridge are secured, are supported from the struts or beams by means of pendent rods, bars, or cables i, which support the latter.

65 The weight of the bridge or other structure to be supported by this truss device or cantalever rests upon the shorter end, D, of the same, while the longer or shore end, E, serves as counterpoise for the same, and is attached 70 to an abutment, F, or similar anchorage.

Having thus described my invention, I claim and desire to secure by Letters Patent of the United States—

In a truss or cantalever device for bridges 75 or similar structures, the combination of the central post or column supported upon a pier or tower, the upwardly-inclined struts or beams bearing with their inner ends against the base of the post or column, the rods or cables extending from the top of the post to the ends of the struts, the rods or cables extending from the middle of the post to near the inner ends of the struts, the rods or cables extending from the ends of the struts to the middle of the post, the inclined or oblique brace connecting the outermost of the rods or cables with the strut of the shore end of the structure, the longer rod or cable extending from the top of the post through the strut at the 90 shore end near the end of the same, and attached to the end of the same, the brace filling or taking up the slack in the said rod or cable and bearing against the under side of the strut, the pending rods or cables, and the 95 stringers and sleepers of the bridge or structure supported by the said pending rods or cables, as and for the purpose shown and set forth.

In testimony that I claim the foregoing as my own I have hereunto affixed my signature in presence of two witnesses.

BENJAMIN F. DAVIS.

Witnesses:

B. T. PALMER,
J. F. CAHILL.
